(57) **CLAIM**

The ornamental design for a pet grooming restraint and training tool, as shown and described.

DESCRIPTION

FIG. 1 is a perspective view of a pet grooming restraint and training tool, showing our new design;

FIG. 2 is a perspective view of FIG. 1, showing that the U-bar can be detached from the L-bar;

FIG. 3 is a perspective view of FIG. 1 thereof, shown in use;

FIG. 4 is a top plan view of FIG. 1 thereof;

FIG. 5 is a bottom plan view of FIG. 1 thereof, showing that the U-bar can be detached from the L-bar;

FIG. 6 is a front elevation view of FIG. 1 thereof;

FIG. 7 is a rear elevation view of FIG. 1 thereof; and,

FIG. 8 is a left side elevation view of FIG. 1 thereof, with the right side elevation view being a mirror image of the left side elevation view.

The broken lines showing a dog, a table, and a clamp represent unclaimed subject matter and form no part of the claimed design.
